UNITED STATES PATENT OFFICE.

LAURA M. MYERS, OF CHICAGO, ILLINOIS.

GAME OR TOY.

1,352,309.

Specification of Letters Patent. Patented Sept. 7, 1920.

Application filed January 20, 1919. Serial No. 272,010.

To all whom it may concern:

Be it known that I, LAURA M. MYERS, a citizen of the United States, residing at Chicago, in the county of Cook and State 5 of Illinois, have invented certain new and useful Improvements in Games or Toys, of which the following is a specification.

This invention relates to a device which may be used as a projectile or manipulated 10 by means of a stick and string in order to coöperate with a board or target in playing a game; said device when manipulated by the stick and string also having certain 15 peculiar movements and being adapted to be utilized as a toy or amusement device.

The objects of this invention are, to provide a game in which a peculiarly novel projectile is provided for coöperation with a board or target; to provide a peculiarly 20 novel creepy device which may be drawn or moved across various surfaces, and when so moved will tend to remain in an upright position, although producing particularly 25 novel movement effects; and, in general, to provide such an improved toy or game as will appear more fully from the following description.

In the accompanying drawings illustrating 30 this invention:

Figure 1 is a plan view of a board or target;

Fig. 2 is a front view of the projectile or 35 movable member with the stick and string attached thereto; and

Fig. 3 is a vertical sectional view through 40 the toy.

As illustrated in these drawings, 4 represents the toy, which may be used as a projectile or which may be actuated by means 45 of a stick 5 and string 6. The toy 4 comprises a substantially cylindrical body or base 7, which is made of any suitable material, but which is preferably made of comparatively soft rubber. The bottom 8 may 50 be made flat or may be slightly beveled, as indicated at 9, or otherwise formed. A piece of cloth or felt 10 is secured to the top of the body portion and preferably extends some distance beyond the sides of 55 the same. This felt member may conveniently be made rectangular, and the string 6 is preferably attached, as indicated at 11, adjacent to one edge thereof. A guide vane is applied to the base, this vane preferably comprising a feather 12, which is inserted

in a hole 13 through the felt and into the base. This feather may be secured in any desired manner, but I prefer to bend the end of the quill back a short distance to form a barb, and then by means of a suitable tool, press the end into the hole, as indicated in Fig. 3, so that the barb or extreme end of the quill will tend to hold the same in position. The unique features of this device may be further accentuated by applying faces or images 14 to the feather in the manner indicated.

When this device is thrown or actuated by means of the stick and string, it may be given a peculiar flying movement, and if 70 allowed to alight on a surface, it will tend to stand in upright position. The string 6 is preferably woven or treated with some stiffening material, so that it will not tend to wind around the device or become entangled. 75 When the device is drawn along the floor or other horizontal surface, it will have a peculiar wabbly upright movement, which tends to furnish much amusement. The device may also be drawn up over vertical, or 80 substantially vertical, surfaces, and in this instance will appear to be walking or creeping up the same, and by drawing the string, for instance over the edge of a table, and pulling the device up, it will appear to be 85 climbing up the side and over the edge on to the top.

When the device is to be utilized in playing a game, a target or board, such as shown in Fig. 1, is provided, having certain spots 90 or figures which are intended to count any predetermined amounts, for instance, as indicated on the drawing. Some of these figures may be made in different colors in order to add to the attractiveness of the 95 game. The board or target is preferably placed in a horizontal position, and the toy may be thrown as a projectile with a view of making it alight on predetermined spots; or it may be manipulated by means of the 100 stick and string, the player trying to throw the device so that it will land on the spots indicated.

It will be noted that this toy may be made in various forms in order to embody the 105 principles of this invention, and the board or target may be constructed in any suitable manner so as to conform to the arrangement herein described, and therefore I do not wish to be limited to the exact construc- 110

tion herein set forth, except as specified in the following claims, in which I claim:

1. A toy comprising a short resilient base member, with a cover of felt over the top 5 thereof and extending beyond the sides a sufficient distance so that the device will tend to stand in upright position, said base having an upwardly projecting vane of light material.
- 10 2. A toy comprising a substantially cylindrical base formed of rubber, a piece of felt secured to the upper surface of said base and extending beyond the sides thereof a sufficient distance so that the center of gravity will be below the piece of felt, and a feather having one end secured in said base.
- 15 3. A toy or the like comprising a substantially cylindrical body formed of rubber and having a slightly concave lower surface, a piece of stiff cloth secured to the upper surface of the body and projecting therefrom, a feather having one end secured in said body and projecting upwardly there-

from, a string attached to the outer edge of said cloth, and a stick to which the opposite end of the string is attached.

4. A toy construction comprising a rubber body having substantially flat upper and lower surfaces, a piece of stiff felt secured to the upper surface and projecting therefrom, and a feather having the end of the quill bent backwardly and inserted through 30 a hole in said felt and into the body portion, the end of the quill serving as a barb to hold the feather in upright position.

5. A game of the character set forth, comprising a board or target having spaces 35 marked with predetermined numbers, and a projectile comprising a resilient body with a feather projecting upwardly therefrom adapted to be projected on to the board, said projectile being provided with a stick and 40 string for manipulating the same, substantially as described.

LAURA M. MYERS.
